UNITED STATES PATENT OFFICE.

CHARLES LINDSEY, OF WAYNESBORO, MISSISSIPPI.

DESIGN FOR A COMBINATION-TOOL.

46,507.

Specification for Design.

Patented Oct. 6, 1914.

Application filed August 26, 1913. Serial No. 786,805. Term of patent 3½ years.

To all whom it may concern:

Be it known that I, CHARLES LINDSEY, a citizen of the United States, residing at Waynesboro, in the county of Wayne and State of Mississippi, have invented a new, original, and ornamental Design for a Combination-Tool, of which the following is a specification, reference being had to the accompanying drawing, forming part thereof.

Figure 1 is a perspective view of the combination tool. Fig. 2 is a top plan view thereof.

I claim:

The ornamental design for a combination tool, as shown.

CHARLES LINDSEY.
